CLAIM

The ornamental design for a foot support block for runner, as shown and described.

DESCRIPTION

FIG. 1 is a top plan view of a foot support block for runner, showing my new design;

FIG. 2 is a bottom plan view thereof;

FIG. 3 is a side elevational view of the free side thereof;

FIG. 4 is an elevational view of the attachment side thereof;

FIG. 5 is a rear elevational view thereof; and

FIG. 6 is a front elevational view thereof.

*FIG. 1.**FIG. 6.**FIG. 2.**FIG. 5.**FIG. 3.**FIG. 4.*
